TAPER CUTTING ADJUSTMENT FOR LATHES

Dean O. Truba, South Gate, and Elmer T. Liller,
Los Angeles, Calif.

Application December 30, 1942, Serial No. 470,618

4 Claims. (Cl. 82—15)

This invention relates to new and useful improvements in taper cutting adjustments for lathes and more particularly to an improved tail stock whereby the tail stock end at work can be held off center and adjusted as required toward the cutting tool.

Another important object of the invention is to provide an adjustable tail stock of the character stated wherein the parts can be readily adjusted to permit cutting of tapers of any desired pitch or length.

Other objects and advantages of the invention will become apparent to the reader of the following description.

In the drawings:

Figure 1 is a fragmentary top plan view fragmentarily showing the tail stock portion of a lathe with the present invention installed.

Figure 2 is a fragmentary front elevational view of the structure shown in Figure 1.

Figure 3 is a fragmentary side elevational view of the structure shown in Figure 1.

Figure 4 is a fragmentary vertical sectional view taken substantially on the line 4—4 of Figure 1.

Figure 5 is a fragmentary horizontal sectional view taken substantially on the line 5—5 of Figure 2.

Figure 6 is a fragmentary vertical sectional view taken substantially on the line 6—6 of Figure 3.

Referring to the drawings wherein like numerals designate like parts, it can be seen in Figure 4 that numeral 5 denotes a lathe tail stock through which is disposed a lathe spindle 6, the stock 5 being provided with the usual lock lever 7.

Numerical 8 denotes a base plate having a tapered stub shaft 9 protruding therefrom and disposed into the hollow spindle 6, where a lock screw 10 works into a longitudinal groove therein. The stub shaft 9 is left hand threaded into the base plate 8.

On the face side of the base plate 8 is a block 11 having a dovetail-shaped formation 12 thereon and outwardly of this is a guide shoulder 13, over which rides the channeled portion 14 of an outer block 15 which has a dovetail-shaped grooveway 16 therein to receive the dovetail-shaped formation 12. A gib 17 is interposed between one side portion of the dovetail formation 12 and one side wall of the dovetail-shaped groove 16, as clearly shown in Figure 4.

The block 11 has a longitudinally extending pocket 19 therein, one end being closed to form a wall 20 through which the smooth portion 21

of a screw shaft 22 is journaled. A hand wheel 23 is provided at this end of the shaft 22, the shaft 22 having a reduced and threaded portion 24 protruding from the smooth end 21 and equipped with a nut 25 for holding the knurled wheel 23 in place, with a tubular hub portion 26 thereof riding against the corresponding end of the block 11. The hub 26 and a shoulder 27 on the shaft 22 cooperate to swivelly mount the screw shaft 22 and prevent longitudinal movement thereof.

In the pocket 19 is a nut 28 held in place by a set screw 29 and as is shown in Figure 5, the screw shaft 22 is disposed through this nut 28.

Small set screws 28a (see Figure 2) are employed for securing the nut 28, when desired.

The remaining end of the screw shaft 22 has a reduced and threaded portion 30 on which the hub portion 31 of a second knurled hand wheel 32 is feedable, the hub 31 having a flanged end portion 33 and a tubular skirt extension 34 capable of binding in place to lock the shaft 22 against rotation.

Obviously, when the hand wheel 32 is loose, rotation of the hand wheel 23 will serve to feed the nut 28 and the outer block 15 by which it is carried, and this obviously adjusts a center pin 35 to the desired off-centered position.

The center pin 35 comprises a ball 36 and a tapered shank extending therefrom, the shank portion being wedged into a tapered opening in a cap structure 37 which is internally threaded for disposition over a stud 38 secured to the block 15.

A set screw 39 is feedable through one side of the cap 37 and against the stud 38 to lock the cap 37 against unscrewing from the stud 38, the set screw 39 being provided with a laterally disposed handle 40, which can be used to rotate the cap 37 in driving the pin 35 against the block to dislodge said pin when desired.

Graduated markings 41, 42 are provided on the blocks 11 and 15 in order that micrometric adjustments can be obtained.

As is clearly shown in Figures 2 and 4, an adjustable stop member 45 depends from a slot in the bottom of the block 15 and is capable of being stopped against a fixed stop member 46 projecting outwardly from the base plate 8.

Obviously, in the operation of this device, the hand wheel 32 can be rotated so as to disengage the flange 33 from the adjacent end of the block 11, thus freeing the shaft 32, so that it may be rotated by the hand wheel 23 in order to move

the slidable block 15, thus carrying the center pin 36 to the desired off-center position.

It will be apparent, that the purpose of the pin 45 and stop member 46 is to stop the block 15 with the pin 35 on dead-center when the block 15 is moved to the left in Figure 2.

The pin 35 has a ball head which will obviously accommodate work moved to any diverged position off of the axis of the lathe, in contradistinction to tapered pins which would obviously cause considerable wear in the work.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A taper cutting mechanism for lathe comprising a pair of tail stock blocks, one of said blocks being fixed against transverse movement, the other block being movably mounted on the fixed block, a threaded cap carried by the movable block and having a central opening, and a tapered center pin positioned in the opening and movable into engagement with the movable block to eject the pin upon a predetermined threading movement of the cap.

2. A taper cutting mechanism for lathe comprising a pair of tail stock blocks, one of said blocks being fixed against transverse movement, the other block being movably mounted on the fixed block and a center pin on the movable block, a screw shaft for feeding the movable block on the stationary block, said shaft provided with a threaded extension and a feedable member on the threaded extension adapted to bind against

one end of the fixed block to prevent rotation of the shaft.

3. A taper cutting mechanism for lathes, comprising a pair of tail stock blocks, one of said blocks being fixed against transverse movement, the other block being movably mounted on the fixed block, a center pin on the movable block, said fixed block being provided with a transverse aperture, a nut on said movable block extending into said aperture, a screw shaft in said aperture engaging said nut for feeding the movable block on the stationary block, a threaded extension on said shaft, a rotatable internally threaded member on said threaded extension, and a shoulder on said member adapted to abut and bind against one end of said fixed block to prevent rotation of said shaft.

4. A taper cutting mechanism for lathes, comprising a pair of tail stock blocks, one of said blocks being fixed against transverse movement, the other block being movably mounted on the fixed block, a center pin on the movable block, said fixed block being provided with a transverse aperture, a nut on said movable block extending into said aperture, a screw shaft in said aperture engaging said nut for feeding the movable block on the stationary block, a threaded extension on said shaft, a rotatable internally threaded member on said threaded extension, a shoulder on said member adapted to abut and bind against one end of said fixed block to prevent rotation of said shaft, dead center-determining stop abutment on the block and micrometer gauge means on said block for indicating the relative position of said movable block.
